UNITED STATES PATENT OFFICE.

EDUARD SCHOENING, OF BERLIN, GERMANY.

WEB-WINDING MACHINE.

SPECIFICATION forming part of Letters Patent No. 789,070, dated May 2, 1905.

Application filed June 23, 1903. Serial No. 162,770.

To all whom it may concern:

Be it known that I, EDUARD SCHOENING, a subject of the Emperor of Germany, residing at Berlin, Germany, have invented certain new and useful Improvements in Web-Winding Machines for Rolling Up Paper, Woven and other Materials in Web Form, fully described and represented in the following specification and the accompanying drawings, forming a part of the same.

My invention relates to winding-machines for winding paper, woven materials, and other goods in web form upon a roller, and has for its object to provide a machine of the character indicated which will automatically and tightly wind the web in a straight and uniform manner.

The invention consists of means controlled by the web for regulating the speed of the roller upon which the web is wound.

The invention also consists in the particular construction and arrangement of parts, as hereinafter described, and pointed out in the claims.

Reference is to be had to the accompanying drawings, forming a part of the specification, and in which similar letters of reference indicate corresponding parts in all the figures.

Figure 1 is a side elevation of a winding-machine having my improvement applied. Fig. 2 is a similar view of the opposite side, and Fig. 3 is a plan view.

In the drawings, *a* is the winding-roller, mounted in the frame *b*, and upon which the web *c* is to be wound. The drive-shaft *d* is mounted in the lower part of the frame and has at one end the pulley *e*, from which the belt *f* passes to the pulley *g* on the shaft of the winding-roller *a*. On the opposite end of the drive-shaft *d* the driving-pulley *h* is loosely mounted, and fixedly secured to said shaft and engaging the driving-pulley is the friction-disk *i*, which forms a coupling for connecting the pulley with the shaft, so that the pulley may be rotated by the belt *j* from a printing or any other suitable machine. The frictional contact of the disk *i* with pulley *h* is adjusted by the screw *k*.

At the rear end of the frame *b* is the guide-frame *l*, which consists of the curved end bars

m and tie-rods *m'*. On the lowermost tie-rod *m'* is mounted the roller *n*, and upon the tie-rods *m'* are adjustably secured, by means of set-screws *n'*, the guides *n*, between which the web passes.

In the upper ends of the standards *b'* of the frame *b* is secured the rod *o*, and in the lower ends of the said standards is mounted the roller *p*. Between the standards *b'*, intermediate of the roller *p* and the rod *o*, is centrally and pivotally mounted a frame *q*, carrying the roller *r* and rods *s* and *t*. On one end of the rod *s* is mounted the worm-wheel *s'*, which meshes with the worm *u'* on the shaft *u*, so that by turning said shaft the frame *q* can be adjusted to increase or decrease the tension of the web. A large wooden roller *v* is mounted in standards on the upper part of the frame *b*, and over which the web passes to the roller *a* after passing over the rod *w* below the roller *v*.

When the pulley *h*, which is connected with the shaft *d* by the friction-disk *i*, is revolved by the belt *j*, the shaft *d* will be revolved and the roller *a*, by means of the belt *f*, will also be revolved, and the web *c* from a printing or other machine will, after passing between the guides *n* over and under the several rods and rollers, as shown in the drawings, be wound upon the roller *a*.

The machine thus far described is of a well-known form and about which there is nothing new.

The feed of the web from a printing or other machine to a winding-machine is irregular, as is also the speed with which the winding-roller takes on the paper, owing to the increasing diameter of the roll of paper, and such irregularity causes the web to be unevenly and irregularly wound upon the winding-roller and a tendency to tear the paper, and it is to obviate this objection and cause the web to be wound smoothly and in a uniform manner that I have devised my improvement, which I will now proceed to describe.

To the journal-boxes *d'* of the drive-shaft *d* are secured the forwardly-projecting brackets *A*, and between the free ends of the brackets is mounted the shaft *B* so as to rock. Upon this rock-shaft *B* are rigidly secured the arms *C*, and

between the free ends of the arms C is mounted the roller D, which at all times engages the web c. The rear ends of the arms C are extended rearwardly beyond the shaft B and are formed 5 into eccentric shoes E, as shown, which are adapted when the roller D and its arms C are elevated by the tightening of the web to engage the brake-wheels F, rigidly secured to the drive-shaft d. In order to counterbalance 10 the roller D, an arm G is mounted on the shaft B and extends rearwardly and is provided with an adjustable weight H on its end, as shown in Fig. 3.

In operation as the roller D rests upon 15 the web c when the web is slack the brake-shoes E on the supporting-arms of the roller are out of contact with the brake-wheels F on the drive-shaft d, so that the said shaft is driven without hindrance or interference; but 20 should the web become taut, due from its being fed slower or from the winding-roller taking up the web more rapidly, owing to its increase of diameter, the tightening of the web will cause the roller D to be elevated and the 25 brake-shoes E on the inner ends of the arms of the roller brought into engagement with the brake-wheels F on the drive-shaft d, checking said shaft and causing a sliding of the friction-disk i on the pulley h, and as the 30 winding-roller a is driven from said drive-shaft the speed of the said roller will be correspondingly reduced, thereby causing a slower winding of the web thereon. It will thus be seen that the speed of the winding- 35 roller is automatically regulated according to the speed of the web, thereby causing the web to be wound tightly and uniformly upon the roller and without any danger of tearing the web.

40 While I have shown and described the brake-shoes as being formed on the ends of the arms of the roller which engages the web, yet it is obvious that these brake-shoes can be separate from the said arms and independently secured 45 to the rock-shaft. I may also use but one brake-shoe and one brake-wheel, and instead of mounting the roller D in two arms, as shown, it may be mounted in a single arm.

Having thus described my invention, what 50 I claim as new, and desire to secure by Letters Patent, is—

1. A web-winding machine having a winding roller or drum, a drive-shaft from which the winding roller or drum is operated, a 55 brake for said shaft, and a swinging member controlled by the web passing to the winding roller or drum and operating the brake, as set forth.

2. A web-winding machine having a winding-roller, a drive-shaft from which the winding-roller is operated, a brake for the said shaft, a swinging member controlled by the web passing to the winding-roller and operating the brake, and a friction-clutch, one

member of which is loose on the drive-shaft 65 to allow for the difference in speed of the said member and the shaft when the brake is applied, as set forth.

3. In a web-winding machine the combination with a winding-roller, a shaft from which 70 the roller is operated, a drive-pulley loose on the shaft, and a friction-coupling connecting the pulley with the shaft, of a roller adapted to engage the web passing to the winding-roller, brake-wheels on the said drive-shaft, 75 and brake-shoes moved in and out of engagement with the brake-wheels by the roller, engaging the web, as set forth.

4. In a web-winding machine, the combination with a winding-roller, a shaft from which 80 the winding-roller is operated, a drive-pulley loose on the shaft, and a frictional coupling connecting the pulley with the shaft, of a rock-shaft, arms carried by the rock-shaft, and having a roller mounted in their free 85 ends, said roller being adapted to engage the web passing to the winding-roller, brake-shoes carried by the rock-shaft, and brake-wheels on the drive-shaft and with which the brake-shoes engage, as set forth. 90

5. In a web-winding machine, the combination with a winding-roller, a shaft, means for operating the winding-roller from the shaft, a driving-pulley loose on the shaft, and a friction-disk fixed to the shaft and engaging the 95 pulley, of a rock-shaft, arms carried by the rock-shaft, a roller mounted between the arms and adapted to engage the web passing to the winding-roller, brake-shoes on the inner ends of the arms, and brake-wheels on the 100 drive-shaft and with which the brake-shoes engage, as set forth.

6. In a web-winding machine, the combination with a winding-roller, a shaft from which the roller is operated, a drive-pulley loose on 105 the shaft, and a friction-coupling connecting the pulley with the shaft, of a swinging support, a roller mounted in the support and adapted to engage the web passing to the winding-roller, a brake-wheel on the said 110 shaft, and a brake-shoe carried by the swinging support and adapted to engage the brake-wheel when the said support is swung by a change in the tension of the web, as set forth.

7. In a web-winding machine, the combination with a winding-roller, a shaft from which the roller is operated, a drive-pulley loose on the shaft, and a friction-coupling connecting the pulley with the shaft, of swinging arms 115 mounted in front of the said shaft, a roller mounted in the arms and adapted to engage the web, brake-wheels on the shaft, and brake-shoes on the rear ends of the said arms and adapted to engage the brake-wheels, as 120 set forth.

8. In a web-winding machine, the combination with a winding-roller, a shaft, means for operating the winding-roller from said shaft,

a driving-pulley loose on the shaft, and a friction-disk secured to the shaft to turn therewith and engaging the pulley, of a rock-shaft mounted in front of the said shaft, arms secured intermediate of their ends to the rock-shaft, a roller mounted in the forward ends of said arms and adapted to engage the web passing to the winding-roller, brake-shoes secured to the inner ends of the arms, and brake-

wheels on the said shaft and with which the 10
brake-shoes are adapted to engage, as set forth.

In testimony whereof I have hereunto set
my hand in the presence of two subscribing
witnesses.
